UNITED STATES PATENT OFFICE.

MARTIN HAWLEY McLANAHAN, OF PHILADELPHIA, PENNSYLVANIA.

TRAIN-SHED.

1,372,307.

Specification of Letters Patent. Patented Mar. 22, 1921.

Application filed February 9, 1918. Serial No. 216,336.

To all whom it may concern:

Be it known that I, MARTIN HAWLEY McLANAHAN, a citizen of the United States, residing at Philadelphia, county of Philadelphia, and State of Pennsylvania, have invented a new and useful Improvement in Train-Sheds, of which the following is a full, clear, and exact description, reference being had to the accompanying drawings, which form a part of this specification.

The type of train shed now much used is a short span, continuous, low roof shed in which the platforms between tracks are lighted by skylights, and the main feature of which is a longitudinal duct over the center of the tracks through which smoke from the locomotive may be ejected directly into the open air. Under favorable weather conditions smoke is thus ejected and remains out of the train shed, but at other times it is blown or floats back through the same duct through which it was ejected, or through parallel ducts, and this returning smoke, combined with steam and other gases remaining under the shed, floats about over the platform to the discomfort and danger of the passengers, and with a hampering effect upon the use and operation of the shed.

Another objectionable feature of this shed is that because of the lack of ventilation, the heat engendered by the skylights over the platforms renders the use of the shed most uncomfortable during the summer months.

The object of my invention is to provide a train shed which will not be open to the objections specified. While my invention is of the short span, continuous, low roof type, it has no other important characteristics in common with train sheds now in use. It provides a positive draft which will not only eject the smoke and gases of combustion from locomotives but will also remove from under the shed all escaping steam, odors and heated air or gas. The invention exhibits other novel features and advantages, as will appear from the following description in connection with the annexed drawings, in which:

Figure 1 is a cross-sectional view of a shed exhibiting one embodiment of my invention.

Fig. 2 is a longitudinal view of the same.

Fig. 3 is a cross-sectional view of a modification.

Fig. 4 is a cross-sectional view of another modification.

Referring, first, to the construction shown in Figs. 1 and 2: Arranged between each two adjacent platforms *a* is a pair of tracks *b*, comprising two parallel tracks arranged side by side and preferably depressed below the level of the platforms. Extending longitudinally between the two tracks of each pair is a series of arches *c*, to which, in longitudinal alignment therewith, are secured a series of longitudinal beams *d* which may be extended downward to form longitudinally extending partitions dividing the space above adjacent tracks.

Extending between beams *d*, at intervals, are transversely extending beams *e*, and connecting alining cross beams, on opposite sides of each supporting arch, are struts *f*. The roof-supporting structure described and shown permits of the employment of comparatively light material, particularly in the transverse construction, adapts the same to be constructed of reinforced concrete and presents a more attractive appearance from the interior than the ordinary low roof train shed. The structure described, however, forms no essential part of the present invention.

The supporting structure described is so shaped as to adapt it to support a roof which, from above each platform, slopes or curves upwardly, adjacent roof sections converging to form a hood *h* over the tracks, the highest point of the hood being between the tracks. Communicating with the central, or highest, part of the hood, are vents in the form of a flue having a series of cross partitions, which form in effect a series of flues *i* extending along the length of the roof. These flues are preferably contiguous, as shown in Fig. 2. There may be a double row of flues, as shown in Fig. 1, or a single row, as shown in Fig. 3, but I do not limit myself to absolutely contiguous flues or to any particular number of rows of flues. The flues are of substantial height, so as to create and maintain a substantial draft. The slope of the roof upward toward these

ffues directs smoke, gases and hot air to the mouth of the flues:

In the common construction wherein a longitudinal duct is provided, there is virtually no draft, the duct being a mere slot in the roof. To carry off the smoke and gases, reliance is placed solely upon the location of this duct directly above the center of the track and upon the natural tendency, under normal conditions, for such smoke and gases to rise. By extending the side walls of a duct of this character a substantial distance above the roof, even without cross partitions, a narrow elongated flue is created which tends to create and maintain a decided draft, and my invention does not necessarily involve the use of the cross-partitions shown; but the use of the cross-partitions greatly enhances the drawing effect of the flue, it being a fact that a plurality of flues of a given total area creates a much better draft than a single flue of the same, or even of somewhat greater area. For the same reason a double row of flues is preferred. While I have shown the flues as of circular shape in cross-section, it is obvious that other shapes will be found effective.

I prefer not to have the roof extend upward smoothly and unbrokenly from above the center of the platform to the flues *i*, but to shape the roof with an abrupt rise at the junction of the platform roof or ceiling with the hood. Each side of the hood has thus a side wall connecting its peaked top with the platform roof. Below and in line with each side wall of the hood is a deflector *k*, which is provided with an opening *m* adjacent to the roof to allow the free passage of air from the platform. This deflector directs the smoke, gases and hot air into the hood and toward the flues. The opening or throat *m* will quicken the natural air currents along its extension, directly ventilate the under side of the platform roof and aid in directing the smoke, gases and hot air into, and confining them within, the hood until they escape by way of the flues. The rise in the roof just above and in line with the deflector aids the draft at the throat *m* and prevents smoke ejected under pressure from being temporarily puffed back under the platform roof. The rise in the roof along this line also prevents the possibility of cinders rebounding and alighting upon the platform.

The platform is provided with a double roof of vault light construction, the under roof *n* being of glass and in the form of an inverted curve, while the upper roof *o*, also of glass, and spaced a considerable distance above the lower roof, is pitched from a central ridge to provide drainage for rain and snow. The spaces between the sky-

lights will be ventilated to prevent heating of the lower surface in summer and the chilling of the same in winter. This space will also be used for lighting conduits and fixtures.

The depression *p* at the junction of the double skylight and the roof of the hood acts as a drain.

The longitudinally extending partition *d*, which divides the hood into separate compartments, one over each track, will preferably be made hollow. Through the hollow partition may extend steam pipes *r* to supply heat, if needed, to aid the draft in heavy weather.

I prefer to suspend from the partition *d* a laterally extending hollow frame *s*, whose lower face slopes upward from its longitudinal center line toward each side, whereby additional currents of air will be directed toward the space above the center lines of the tracks. The top surface of the frame *s* forms continuous gutters or catch-basins *g* for collecting soot and cinders.

That part of the deflector *k* below the strut *f* may be made removable in order to provide space for the pantograph in the event of the future use of the shed for electric trains.

The construction shown in Fig. 3 is similar to that shown in Fig. 1, and is similarly lettered, with the following exceptions. Only a single row of flues *t* is provided. The longitudinal partition *d* is dispensed with and two of every three successive cross-beams *u* are hung direct from the arches *c*, the third cross-beam, which is located directly over the junction of two adjacent arches, being supported from an upright.

In the construction shown in Fig. 4, the lines of arches *w* are located along the longitudinal center lines of the platforms. The cross-beams *x* curve upward from their supporting arches toward the space above a line midway between the two tracks. Struts *y* reinforce the cross-beams and permit of the use of light material in the transverse construction.

In all the figures the space over the tracks between the cross-beams and struts is closed by means of partitions *z* dividing the hood into compartments, whereby possible disturbances of draft by longitudinal air currents will be prevented and the heat and gases from the locomotives will be locally confined, thus increasing the draft action of the flues. Supported from the cross-beams is a partition *q*, which divides each compartment of the hood longitudinally, this partition being extended upward to divide the flues into two rows. Beneath the partition *q* is positioned an inclosed longitudinally extending hollow frame *j* performing the function of the similarly lo-

cated hollow frame in Fig. 1. The lower face of frame *j* slopes upward from its longitudinal center line toward each side, to direct the air currents upwardly from between the tracks toward the space above the longitudinal center line of each track.

In all the constructions, I provide, between each platform base and the adjacent track base, a groove or gutter 5 and build 10 the platform so that it overhangs this gutter. The depth of the gutter is sufficient to permit car inspectors to walk along the same, while the train is standing in the shed and receiving and discharging passengers and baggage.

Having now fully described my invention, what I claim and desire to protect by Letters Patent is:

1. A train shed comprising a roof provided with a longitudinally arranged row of separate and independent and substantially contiguous flues communicating with the interior of the shed and extending a substantial distance above the shed roof, the upper 25 ends of the flues being unobstructed and opening upwardly.

2. A train shed comprising a pair of tracks and a hood extending over both tracks with sides arranged to divert smoke, steam 30 and gases from a locomotive on either track upwardly and inwardly to a central longitudinally extending duct in the hood extending above the space between the tracks.

3. A train shed comprising a pair of tracks and a hood arranged above the tracks with sides arranged to divert smoke, steam 35 and gases from a locomotive on either track upwardly and inwardly to a longitudinally extending duct in the hood extending above the space between the tracks, and a row of upright flues communicating with the hood and opening upwardly so as to afford a 40 strong draft which assists in the withdrawal from the hood of smoke, steam and gases discharged thereinto.

4. A train shed comprising a roof and two parallel, contiguous rows of separate and independent flues, said rows of flues 45 extending longitudinally of the shed and extending a substantial distance above the shed roof.

5. A train shed comprising a pair of parallel tracks, and a roof sloping upward from above each track toward the space between 55 and above the tracks and there provided with a duct for the discharge of smoke and gases.

6. A train shed comprising a pair of parallel tracks, a roof provided with a centrally located duct above the space between the tracks, and means to deflect smoke, gases 60 and air from above each track laterally toward said duct.

7. A train shed comprising a pair of 65 tracks, and a hood, having a sloping roof,

arranged above the space between the tracks and overhanging both tracks, and a row of separate upright flues communicating at their lower ends with the hood between its sides.

8. A train shed comprising a pair of tracks, and a hood, having a duct centrally between the tracks for escape of smoke and gases, arranged above the space between, and overhanging, the tracks and provided 70 with downwardly extending side walls positioned outside the longitudinal center lines of the two tracks, whereby lateral escape of smoke and steam from locomotives will be largely or wholly prevented 75 and the same diverted to the discharge duct.

9. A train shed comprising a pair of tracks, and a hood whose roof slopes upward from each side toward the space between the tracks and there provided with a duct for the escape of smoke and gases, the sides of the hood extending downward 85 and forming smoke and gas deflectors.

10. A train shed comprising two platforms, a pair of tracks between the platforms, and a roof sloping upward from each platform to the space above and between the tracks, the roof being there provided with a duct for the escape of smoke 90 and gases.

11. A train shed comprising a platform, a pair of tracks, and a roof sloping upward from the platform to the space above and between the tracks and there provided with a duct for the escape of steam and gases, 100 said roof being offset to form an abrupt rise above the space between the center line of the track and the platform to prevent smoke ejected under pressure from being puffed back over the platform.

12. A train shed comprising a pair of tracks, a platform, a roof extending over the platform and shaped to form a hood above the tracks, the hood being provided 110 with a discharge duct between the inner rails of the tracks, and a longitudinal deflector extending downward from the roof above the space between the center line of the track and the platform.

13. A train shed comprising a pair of tracks, a platform, a roof sloping upward toward the space above and between the tracks and provided with a discharge duct, 120 said roof having an abrupt raise along a longitudinal line between the center line of a track and the adjacent platform, and a deflector extending below the platform roof in substantial alinement with said raise.

14. A train shed comprising a pair of 125 tracks, a platform, a roof sloping upward toward the space above and between the tracks and provided with a discharge duct, said roof having an abrupt raise along a longitudinal line between the center line of 130

- a track and the adjacent platform, and a deflector extending below the platform roof in substantial alignment with said raise and provided with a longitudinally extending opening to allow ventilating and smoke and gas deflecting currents of air to flow from below the platform roof into the hood.
15. A train shed comprising a pair of tracks, a hood arranged to overhang the tracks and provided with a discharge duct above the space between the tracks, and a partition within the hood extending longitudinally above the space between the tracks.
16. A train shed comprising a pair of tracks, a hood arranged to overhang both tracks, a partition within the hood extending longitudinally above the space between the tracks, two contiguous rows of flues above and communicating with the interior of the hood, one row of flues being arranged on one side of said partition and the other row on the other side of said partition.
17. A train shed comprising a pair of tracks, a hood arranged to overhang the tracks and provided with a discharge duct above the space between the tracks, a partition within the hood extending longitudinally above the space between the tracks, and a frame projecting laterally on both sides of the lower part of the partition and having a lower face inclined upward toward its opposite edges.
18. A train shed comprising a platform, a pair of tracks, a hood above the tracks having a discharge duct above the space between the tracks, and a double skylight above the platform, the roof of the hood sloping upwardly toward the discharge duct, the lower skylight sloping upward toward the hood, and the upper skylight sloping downward toward the roof of the hood.
19. A train shed comprising pairs of tracks alternating with parallel platforms, a roof comprising double skylights overhanging the platforms and hoods overlying the tracks, the hoods each having a roof sloping upward from each side toward its longitudinal center, there being a deflecting offset between each lower skylight and each adjacent hood roof, lengthwise extending deflectors arranged beneath said offsets and provided with openings adjacent the side edge of the lower skylight, and a lengthwise extending row of flues arranged between each pair of tracks and extending substantially above the peak of the hood.
- In testimony of which invention, I have hereunto set my hand, at Philadelphia, Pa., on this 7th day of February, 1918.

MARTIN HAWLEY McLANAHAN.
